 Davidson Manufacturing Corporation, Chicago,
 Ill., a corporation of Illinois

Application July 9, 1936, Serial No. 89,703

10 Claims. (Cl. 230—140)

My invention relates in general to fluid pressure devices and has more particular reference to a rotary apparatus more particularly adapted for use in high compression of fluid media and adapted also for producing high vacuum conditions, the invention including novel features having general application in fluid pressure or hydraulic apparatus. The present application comprises a continuation in part of my co-pending application Serial No. 743,196, filed September 8, 1934, for Compressor.

An important object of the invention is to provide a fluid pressure device having improved means incorporated therein for sealing the device against fluid leakage.

Another important object is to provide a pump for developing pressure in a fluid work medium including means incorporated in the pump for utilizing the pressure developed in the work medium to assist in sealing the pump.

Another important object is to provide an hydraulic or fluid flow device having facilities for lubricating the operating parts of the device including an arrangement whereby the medium used to lubricate the parts is applied under pressure to seal the device against fluid leakage therein.

Another important object is to seal a device of the character described by applying at places where leakage is likely a sealing medium under pressure in excess of the maximum fluid pressures developed by the device when in operation.

Another important object is to provide a rotary pump particularly well adapted for use in compressing a gaseous work medium such as air, ammonia gas, and the like, but suitable, of course, for pressure and vacuum pumping purposes generally, said pump comprising a cylinder and eccentric piston forming a work chamber and cooperatively associated and relatively movable to provide the fluid forcing, evacuating or compressing function upon fluid delivered in said work chamber, one of said elements carrying a blade having bearing relationship on the other to form a driving connection therebetween.

Another important object is to provide a rotary fluid pressure device comprising a cylinder and a relatively eccentric piston wherein the cylinder comprises an annular rim, carrying an inwardly extending radial projection or blade, the opposite sides of the rim carrying end plates secured thereto in position clampingly engaging the opposite side edges of said blade, whereby to afford a structure which can be readily fabricated and assembled and which, at the same

time, provides adequate sealing at the junction of the side edges of the blade with the end plates of the cylinder.

5 A further object is to mount the piston within the cylinder on an eccentric portion of a shaft, which also has a portion or shank extending out through a side wall of the cylinder and to form the channel, through which the work material is passed to the piston, as a longitudinal passage formed in the said shaft. A further object is to form a duct connecting with the work space and including a portion extending substantially radially in an end wall of the cylinder.

15 A still further object is to provide a resilient seal between the communicating ends of a channel in which the work medium is conducted through the piston and the radial duct in the cylinder wall.

20 Another object is to provide means to adjust the eccentricity of the piston axis with respect to the axis of the cylinder by angularly adjusting the piston-carrying shaft in its support so as to adjust the position of the eccentric piston-carrying portion of the shaft within the cylinder.

25 Another important object is to form the cylinder with an axle at one end and an opening at the other providing a thrust bearing, the cylinder being mounted in a casing formed with a bearing for said axle and with a thrust bearing for directly supporting the other end of the cylinder so that the fluid under pressure delivered in the housing may act upon the cylinder to force it axially against the thrust bearing and thus assist in sealing the cylinder to the frame around the end opening of the cylinder; a further object being to provide the housing with a projection forming a sleeve extending centrally of said thrust bearing and through the opening in the end wall of the cylinder and to mount the piston-carrying shaft in said sleeve.

30 Another important object is to form the piston as a hollow element or shell having an internal chamber or chambers and to provide for delivering a lubricant, under pressure, to said chambers as the piston rotates on its eccentric shaft within the cylinder, said piston being formed with openings communicating said chambers with the inner faces of the cylinder end plates.

35 Another object is to provide a device of the character mentioned and having a lubricating system designed to afford improved sealing against passage of the working fluid between the contact end surfaces of the piston and the end

plates, the bearing surfaces on which the blade is carried in the piston, the thrust bearing carrying the directly supported end plate, the journal in which the shaft carrying the other end plate is mounted, and the end of the piston shaft where it engages the surface of the end plate around the axially opening end of the radially extending inlet channel therein, these being points where fluid leakage is apt to occur.

A further object is to form the casing to receive the lubricant after the same has performed its sealing and lubricating function and to provide a circulating lubricant system for receiving the used lubricant and returning it under increased pressure to the chambers of the piston; a further object being to cool the sealing and lubricating medium prior to delivery under pressure to the device.

Another object is to provide a duct connected with the work space and including a portion extending longitudinally in the cylinder shaft; a further object being to provide a sealed chamber about the shaft communicating with said duct.

Still another object is to provide apparatus adapted to produce unusually high pressures in a single stage, actual apparatus embodying the invention having been operated, regularly and continuously to compress air at pressures substantially in excess of four hundred pounds per square inch, the single stage device further being operable to produce a vacuum of 99.95%, that is to say, a vacuum of 29.05 millimeters with a barometer of 29.0625 millimeters.

These and other numerous objects, advantages, and inherent functions of the invention will be apparent from the following description, which, taken in connection with the accompanying drawings, discloses a preferred embodiment of my invention.

Referring to the drawings:

Figure 1 is a diagrammatic view of a fluid forcing device embodying my present invention, including a system for lubricating and sealing the device;

Figure 2 is a diagrammatic view showing a modified arrangement of the lubricating and sealing system;

Figure 3 is a sectional view taken substantially along the line 3-3 in Figure 1;

Figure 4 is a fragmentary view of a part of the device;

Figure 5 is a sectional view taken substantially along the line 5-5 in Figure 4;

Figure 6 is a sectional view taken substantially along the line 6-6 in Figure 3;

Figure 7 is a sectional view showing a modified arrangement of a portion of the device;

Figures 8, 9, 10 and 11 are perspective views of parts of the device; and

Figures 12 and 13 are modified arrangements of the device.

To illustrate my invention, I have shown on the drawings an hydraulic apparatus comprising a rotary machine especially well adapted to function as a compressor for gaseous media and adapted also to operate as a pump for fluid forcing or evacuating purposes, although it will be obvious that certain features of the invention may have general application in any type of hydraulic or fluid flow apparatus.

Apparatus embodying my invention, however, is characterized by the provision of means for sealing the same in order to provide unusually high efficiency of operation so that where used as a vacuum or fluid forcing pump or compressor,

devices embodying my present invention will develop heavy pressures in the work medium or exceedingly high vacuum conditions, as the case may be, and, at the same time, will operate at great efficiency so that the invention will have great utility more particularly where the work medium is of gaseous character.

To provide the foregoing characteristics, I utilize certain novel structural arrangements whereby the operating parts of the units are sealed effectively against the escape of the working medium, said sealing means including not only the particular form of parts employed but also the cooperation of said parts with each other and with the compressed work medium, as well as the provision of an improved lubricating method and system whereby the operating parts of the device are adequately lubricated at all times to ensure quiet and efficient operation and the lubricating medium is itself applied under pressure with fairly definite limits to assist in sealing the device.

The pump or compressor, which I have shown in order to illustrate my present invention, comprises essentially a pair of cooperating parts forming a cylinder 11 and a piston 13, which are mounted for relative movement in order to accomplish the fluid-forcing or compressing function of the device. The cylinder and piston are mounted in a frame or casing 14, and are preferably both mounted for rotation about relatively eccentric parallel axes, with the piston in contact with the inner surface of the cylinder and, since the inner diameter of the cylinder is larger than the diameter of the piston, a crescent shaped working space 15 is defined therebetween.

The frame or casing 14 provides a closed housing, in which the elements 11 and 13 are mounted and the work medium is delivered into the work chamber preferably through a channel 51 extending axially through the piston and thence radially through a duct 49, which is formed in the cylinder walls. The casing 14 may be of any suitable form, but I prefer to form the same as a pair of cooperating parts, one of which is formed with a base 16, and upstanding walls, including an end wall 18 and preferably cylindrical side walls 22 forming with the end wall a preferably cylindrical compartment open at one end. The other casing part 24 comprises a preferably circular plate adapted to fit upon and close the open end of the compartment defined by the walls 18 and 22. The walls 22 and 24 are preferably formed with an interfitting tongue and groove formation 26 to seal the joint therebetween and the parts may be secured together in any desired fashion as by means of the bolts 28.

One of the cooperating parts, preferably the cylinder, is provided with means comprising an axle 17 for driving the same. The cylinder preferably carries a blade 19 extending in a substantially radial slot 20 formed in the piston so that rotation of the cylinder by means of the shaft will cause rotation of the piston through the driving connection afforded by the blade 19. The piston is mounted for rotation on a preferably stationary shaft 21, which is mounted on the frame 14 in position extending into the cylinder to support the piston therein. As the cylinder and piston are thus rotated in unison about the relatively eccentric axes, the crescent-shaped work space 15 will be caused to travel relatively around the cylinder so that a working medium introduced into the cylinder through a suitable inlet opening 32 on one side of the blade

19 will be drawn into the work space 15 and eventually delivered on the side of the blade opposite from the inlet. The medium may be expelled through a suitable exhaust opening 34, on the side of the blade 19, opposite from the inlet port. While I have shown my present invention as applied in a rotary compressor or pump, in which both the cylinder and the piston are rotated in order to pump the work medium from the inlet port 32 to the outlet 34, it will be obvious that many features of the invention may be applied in similar arrangements, in which one of the cooperating fluid-forcing elements is stationary, while the other rotates about an axis eccentric with respect to the axis of the stationary member to thus accomplish the fluid-forcing function; and I do not wish to limit my invention, necessarily, to a device in which both the piston and cylinder rotate.

I prefer, however, to arrange the parts so that the cylinder at least rotates, and, to this end, and further to simplify the construction and assembly of the cylinder, I prefer to form the same as an assembled structure comprising an annular element or ring 23 on the opposite ends of which are mounted circular discs 25, forming end plates, the ring and end plates being secured together in any suitable fashion, as by means of a plurality of spaced apart fastening elements preferably comprising bolts 27 applied at the peripheral edges of the end plates and extending into the edges of ring 23. One of the end plates 25 is fixed on the shaft 17, which is journaled in a bearing 29 formed in the frame 14. This bearing is preferably of the ball or roller type, although a bushing may be utilized if desired. A shaft seal 31 of any suitable form may be applied to the shaft, the seal shown being particularly well suited for sealing against the leakage of fluid along the shaft. The seal 31, preferably comprises a pair of annular cups 32' embracing the shaft 17 and urged oppositely thereon by a spring 34' to seat sealingly on the wall portions through which the shaft extends, the spring serving also to compress sealing means into the cups 32 and upon the shaft.

The other of the end plates 25 is preferably formed with an axial opening 35 defined by an annular boss 35 and the frame 14 is provided with projecting means 37 extending within said opening 33 and affording a bearing, on which the end plate 25 may be directly journaled, suitable preferably roller bearing means 39 being interposed between the surfaces defining the channel 33 and the outer surfaces of the projecting frame portion 31. The bearing means 39 may, of course, be of any suitable form, and ball or roller bearings are contemplated, although, as shown in the illustrated embodiment, I may utilize an inner sleeve 41 slidably supported on the projecting frame portion 31, a second sleeve 43 surrounding and slidably fitting the sleeve 41 and slidably fitting into the channel 33 of the end plate. A thrust bearing comprising a washer 45, with which the ends of the boss 35 and the sleeve 43 have bearing engagement, is also provided, said thrust washer, in turn, sliding upon an embossment 47 formed in the frame 14 at the base of the projecting frame portion 31. The embossment 47 also furnishes bearing support for an end of the sleeve element 41.

It will be noted that the cylinder has no journal opening, other than that defined by the boss 35, through which leakage of the fluid medium may occur and the thrust bearing 45, operating in

conjunction with the fluid pressure of the compressed medium in the casing 14, operates to firmly seal the cylinder at the thrust bearing. The fluid medium under pressure in the casing exerts a uniform pressure on all of the external cylinder surfaces exposed within the casing. The exposed area of the cylinder on the side carrying the axle 17 is larger than the area on the side having the thrust bearing, so that the resultant pressure on the cylinder will urge it toward the right, viewing Figure 1 of the drawings, in a direction causing the thrust washer to be squeezed between the cylinder boss 35 and the frame embossment 41. This will firmly seal the cylinder against the passage of the compressed fluid into the cylinder through the bearing 39 with consequent loss of efficiency. The sealing effect provided at the thrust bearing, of course, increases with high pressure in the casing.

It is not, in many cases, essential to depend upon the foregoing method of utilizing the axial thrust imparted to the cylinder by the compressed medium for sealing against leakage, since the seal accomplished between the contacting end surfaces of the piston and the end plates of the cylinder will usually be sufficient, particularly where a sealing and lubricating medium is delivered under pressure between said contacting surfaces, to seal the same against leakage of the work medium therebetween. In order to reduce the mechanical losses due to friction at the thrust washer 45, I may, of course, replace the same with a ball or roller bearing, which will not only reduce end thrust by tending to equalize the external pressures exerted on the opposed ends of the cylinder, but also reduce friction at the thrust bearing.

One of the end plates 25 is formed with a radially extending duct 49 opening at one end on the inner face of the plate substantially at the axis of the cylinder; and the shaft 21, on which the piston is mounted, is formed with a longitudinal channel 51, which opens at the inner end of the shaft opposite the axially opening end of the duct 49, so that when the parts are assembled, the channel 51 is in communication with the duct 49 for all relatively operating positions of the piston and cylinder. The duct 49 extends radially in the end plate and opens on the inner surface of the plate near the periphery thereof, said opening being arranged in the surface of the plate adjacent one side of the blade 19 and forms an inlet opening 32, through which the work medium may be delivered to the compression space 15.

The channel 51 in the shaft 21 is preferably enlarged at the end of the shaft facing the axially opening end of the duct 49, and a resilient seal is arranged in said enlarged channel portion. This resilient seal preferably comprises a sleeve 52 fitting into the enlarged portion of the channel and having a flange overlying the end of the shaft 21 in position to engage the inner face of the end plate around the axially opening end of the duct 49.

The channel 51 also carries yielding means, such as the helical spring 56, acting between an internal shoulder in the channel and the inner end of the sleeve 52 in order to yieldingly urge the sleeve against the end plate whereby to provide a seal for preventing escape of the fluid medium passing through the channel 51 and duct 49.

The high pressure within the casing 14 to

which sleeve 52 is subjected externally tends to supplement the pressure of spring 56.

An outlet opening 34 is also formed preferably in one of the end plates and may, of course, be formed in the end plate having the inlet channel 49, although I prefer to form the outlet opening in the other end plate. Alternately, the outlet opening may be formed in the cylindrical element 23. The outlet opening, in any event, opens within the cylinder adjacent the blade 19, on the side of said blade opposite from the inlet opening. I prefer also to slightly relieve the inner surface of the ring 23 as at 53 opposite the outlet opening.

The outlet 34 is preferably provided with a valve 36, permitting the compressed fluid medium to escape from the cylinder into the casing 14, but preventing reverse travel of the fluid into the cylinder through the outlet 34. This valve may be of any suitable or convenient form, but I prefer to utilize a flap valve and to this end may form the outlet 34 with an outstanding annular ridge 38 by fitting a sleeve 42 snugly into the opening 34 with the end of the sleeve projecting to form the ridge. A blade of spring material 44 is anchored on the cylinder in position to normally overlie and close the open projecting end of the sleeve 42. Excessive opening movement of the resilient closure strip 44 is prevented by a substantially rigid stop bar 46 fastened to the cylinder preferably by the same fastener 48, which holds the strip 44 in place.

The shaft 21, on which the piston is supported, has a portion extending in and supported by the projecting frame portion 31, said projecting portion being formed with a channel for receiving the shaft so that the axis of the supported portion is eccentric with respect to the rotary axis of the cylinder. The shaft is mounted so that its inner end may extend within the cylinder in position to support the piston, while the outer end extends outwardly of the frame and is preferably threaded as at 55 to receive a nut 57 in order to lock the shaft in adjusted position. The inner end of the shaft, which lies within the cylinder, preferably comprises an eccentric portion 59 (Fig. 10), on which the piston is mounted for rotation by bearing means 61, which may be of sleeve-like character as shown although ball or roller bearings also are contemplated. The end of the shaft 21, which projects outwardly of the frame, is preferably provided with a non-circular head 63 adapted for the reception of a turning instrument whereby the shaft may be turned in the frame portion 31 in order thus to adjust the position of the eccentric piston-carrying portion 59. It will be obvious that the spacement of the piston and the inner wall of the cylinder at the point of contact, therebetween may be accurately adjusted by turning the shaft 21, so that the cylinder and piston support bearings need not be located with extreme accuracy, thus reducing manufacturing costs, yet the piston may be accurately adjusted with respect to the cylinder to obtain a most efficient pumping contact therebetween, it being understood, of course, that in order for maximum efficiency, the piston should contact snugly with the inner surface of the cylinder but that the contacting pressure therebetween should not be excessive, otherwise there will be undue wear set up in the piston and cylinder bearings. The adjustment also may be used to compensate for worn bearings and other support parts as well as manufacturing inaccuracies, so that pumping efficiency may be ob-

tained and maintained without increasing but in fact reducing the cost of manufacture. The lock nut 57, of course, secures the shaft in its adjusted position. The frame 14 is formed with

5 an externally threaded boss 65 through which the outer end of the shaft 21 projects from the frame, and I provide a removable cap 67 adapted to be threadingly secured to said boss in order to enclose the outer end of the shaft 63 to 10 protect the projecting end of the shaft and to prevent the escape of fluid along the shaft between it and the sleeve 37.

The frame or casing 14 is preferably formed with a duct 69 opening on the outer surfaces of the casing and extending to the channel in which the shaft 21 is supported. The shaft 21 also is provided with an opening 71, which is elongated circumferentially of the shaft and located in position to communicate the channel 69 of the frame with the channel 51 in the shaft in all of the adjusted positions of the shaft. The casing 14 is also provided with an outlet communicating with the interior of the casing so that work medium, introduced to the compressor through the inlet channel 69, may travel thence through the communicating channels 51, in the piston shaft, and 49, in the cylinder end plate, to the inlet port 32. The medium thus introduced through the inlet port 30 may then be passed through the working chamber 15 as a result of the relative movement of the fluid-forcing parts 11 and 13 and be expelled through the one-way outlet 34 into the interior of the casing 14 and escape thence through the casing outlet 73.

In Figure 6 of the drawings I have shown the form wherein the bearing 29 comprises a sleeve bearing. In Figure 7 a construction embodying a roller bearing 29 is illustrated.

In Figure 6 also the medium is conducted to the work space through conduit means comprising the channel 51 in the piston support shaft, which channel 51 communicates with the radially extending duct 49 at the approximate center of the end plate in which said duct is formed. In this construction the duct opens inwardly on the inner face of the end plate. I may, however, as shown in Figures 12 and 13, arrange the inlet duct as a channel 119 extending in the shaft 17 and communicating with the radial duct 49 at the approximate center of the end plate. In such an arrangement I prefer to have the duct 49 not open upon the inner face of the end plate opposite the end of the piston-carrying shaft, 50 which shaft also need not be channeled to form the inlet 51 but may, if desired, be channeled to provide an oil inlet duct in place of the duct 113, shown in Figure 6.

Where the embodiment having the channel 119 is employed, I prefer to arrange an extension 121 on the end of the sleeve-like housing portion 30, said extension having means forming a chamber through which the shaft 17 extends and the duct 119 opening laterally of the shaft into said chamber. A fluid delivery pipe 123 may be connected to the chamber for delivering the fluid work medium.

In Figure 12 I have shown an arrangement particularly adapted where the fluid forcing device is used as a suction or exhaust pump, the openings in the chamber-forming element 121 through which the shaft extends, being sealed by one of the sealing cups 32 of the seal 31 within the sleeve 30, and the other wall opening of the chamber 121 being sealed by a spring pressed,

cup-shaped element 125 applied on the shaft outside of said chamber. During the operation of the device as a suction pump the pipe 123 will form a suction connection and the discharge 13 may be arranged to discharge at atmospheric pressure.

In Figure 13 the chamber-forming means 121 is sealed at the opening through which the shaft extends by sealing means 127, similar to the sealing means 31, the sealing means 127 being applied and arranged entirely within the chamber 121. With this arrangement the fluid forcing device may be operated as a compressor with the pipe 123 connected to atmosphere or similar low pressure source of the fluid work medium to be compressed and the discharge 13 forms the high pressure outlet. The structure illustrated may also operate with the duct 13 connected to an oil separator connected with the circulating system 115 in order to abstract any oil which may be discharged from the apparatus with the compressed work medium through the outlet 13.

In order to construct a device capable of developing high compression in the working medium, or an exhaust pump capable of developing high vacuum, it is necessary to prevent leakage of the medium from the work space 15. Leakage causing loss of compression may occur, for instance, from the working space between the sides of the piston and the end plates and thence through the piston bearing and along the shaft 21. Leakage may also occur from the high pressure or exhaust end of the working chamber past the blade 19 to the low pressure end of the work space, such leakage occurring between the side edges of the blade and the contacting surfaces of the cylinder end plates, or between the blade and the surfaces of the cylinder and piston with which the blade engages. In order to reduce leakage around the blade from the high pressure end of the work space directly to the low pressure end, I prefer to mount the blade 19 rigidly in the cylinder. To this end, the ring member 23 is provided with a slot 75, in which the edge of the blade is securely fastened. Alternately, the blade may be formed as an integrally inwardly extending projection on the ring. The blade also has a width between its opposite edges exactly equal to the width of the ring 23 so that when the end plates 25 are clamped together upon the ring, the opposed side edges of the blade will be firmly clamped against the facing surfaces of the end plates in order thus to prevent leakage therebetween. If desired, in order to provide a more satisfactory seal at the side edges of the blade, the same may be made slightly wider than the ring 23 and the end plates may be grooved in order to receive the opposite edges of the blade in a fashion similar to that illustrated for the attachment of the blade in the groove 15 of the ring. In order to firmly secure the blade in mounted position in the cylinder, the same is preferably formed with a channel 11 to snugly receive an anchoring pin 19, which extends entirely through the blade and projects at its opposite ends from the opposite side edges of the blade. The projecting ends of the pin 19 are received in registering sockets 81 formed in the end plates.

It will be noted that the blade is fixed with respect to the cylinder and that there is no relative movement therebetween to facilitate leakage between the edges of the blade and the cylinder portions with which they engage. The blade, however, in the construction illustrated, neces-

sarily has relative movement with respect to the piston. The blade, as heretofore described, is received in a slotted portion of the piston and, during the relatively fluid forcing movement of the cylinder and piston, will have a rocking and reciprocating movement in the slotted portion of the piston. In order to seal the device against fluid leakage between the blade and the surfaces of the piston with which it cooperates, I form 5 the opposite sides of the slot 20 with semi-cylindrical depressions 83 adapted to receive semi-cylindrical bearing blocks 85 snugly therein. The bearing blocks 85 have flat surfaces having sliding engagement with the opposite faces of the blade, 10 said bearing blocks having a length such that their opposite ends bear upon the opposing faces of the end plates 25. The entire arrangement of the bearing blocks, piston slot, and blade is such as to provide snugly fitting slide surfaces of adequate area to seal against the escape of the working medium around the blade from the high pressure or outlet side of the blade to the low pressure or inlet side, and this effect is increased because the blade is utilized to drive the piston in a direction 15 such that the bearing element 85, which engages the surface of the blade facing the high pressure or exhaust end of the work chamber, is in compression between the blade and the side of the slot so that the sealing effect at this point is improved by the back pressure of the medium being compressed in the work chamber and this sealing effect, of course, increases with higher pressure.

In order to lubricate and assist in sealing the 20 operating parts against the escape of the work medium, I provide an improved system wherein the piston is provided with internal chambers 93 opening laterally on the piston surfaces in contact with the end plates of the cylinder. The piston is also provided with ducts 95 communicating the chamber 93 with the slot 20 in the bearing block seats 85 thereof. The opposed side surfaces of the piston are also provided with annular grooves 97, which are connected together by ducts 99 extending through the piston. These ducts 99 in turn are connected to the piston bearing 61 and the internal chambers 93 by means of ducts 101.

The piston is mounted in the cylinder so that 25 a portion of a groove 97 is at all times opposite a depression 103 formed in the face of the end plate carried on the shaft 17 and a conduit 105 through said end plate connects the depression with a longitudinal oiling channel 107 in the shaft. The oiling channel has branches 109 and 111 leading to the bearing 29 and to the seal 31.

The piston is mounted so that the groove 97 has a portion which at all times opens upon the bearing 39 and also upon a duct 113 formed in 30 the wall of the housing 14. Means 115 comprising lubricant circulating apparatus, including a pump 117, for withdrawing the lubricant from the fluid forcing device, cooling the same, if desired, by means of a refrigerator 118 which may 35 be included in the system 115, and delivering the lubricant under pressure to the duct 113 from whence the lubricant is delivered to the cylinder bearing 39, the piston bearing 61, the shaft bearing 29, and the seal device 31. The lubricant

40 is also delivered into the chambers 93 and thence between the contacting end surfaces of the piston and end plates of the cylinder and also into the groove 20 behind the bearing blocks 85 in order to adequately lubricate the working surfaces and 45 assist in sealing the pump. The lubricating and 50

sealing medium may be returned to the circulating system 115 through an outlet 119' from the seal 31.

The system 115 may also be connected to deliver the sealing and lubricating medium under pressure through the opening 119' to the seal chamber from whence it may flow into the piston and accomplish its sealing and lubricating function, being returned to the circulating system through the opening 113. In either case, the housing may be provided with a sump 91 to catch any oil dripping from the cylinder, and return such oil to the circulating system.

A check valve 117 is preferably included in the system 115 in order to determine the pressure, under which the lubricant is delivered in the fluid forcing device. The system 115, since it is connected with the sump 91, is at the pressure prevailing within the casing 14 on the suction side of the lubricant forcing pump of the system 115 so that the lubricating and sealing medium will be delivered to the fluid forcing device at a pressure appreciably in excess of that in the housing 14. That is to say, in excess of the highest pressure developed by the operation of the device 11. By adjusting the valve 117 the sealing medium may thus be delivered to the working parts of the fluid forcing device, and more particularly between the end surfaces of the rotor and the engaging surfaces of the end plates 25 at a pressure in excess of the maximum pressure developed in the work space.

I find it desirable to regulate the delivered pressure of the sealing medium within limits which may be determined empirically and which apparently depend, at least to some extent, upon the size, capacity and construction of the fluid forcing device, and also upon the pressure or vacuum conditions to be produced.

When the fluid forcing device is operated as a compressor, I find that pressure of 100 pounds per square inch may be had at substantially maximum efficiency without pressure in the lubricating medium, it being sufficient merely to supply lubrication alone and to rely upon the accuracy and fit of the parts to prevent leakage of the work medium. Where pressures in excess of 100 pounds per square inch are to be developed, however, I find it is necessary, in order to eliminate leakage of the work medium and consequent loss of operating efficiency in the fluid forcing device, to apply the lubricant as a sealing medium, in the manner heretofore described, under pressure while the exact pressure of the sealing medium to produce operation at maximum efficiency is difficult to determine I find that a pressure of approximately 5 pounds per square inch in excess of the maximum pressure of the work medium in the fluid forcing device is necessary where the device is operated to produce pressures of the order of 350 pounds per square inch, and I assume that pressures between 100 and 350 pounds at the discharge of the compressor will require corresponding excess lubricant pressures ranging between 1 and 5 pounds, and that pressures in excess of 350 pounds at the discharge of the compressor will require corresponding pressures in the sealing medium in excess of 5 pounds. I have, however, been unable to determine any material effect resulting from a reduction in the excess pressure in the sealing medium below 5 pounds when operating the compressor at between 100 and 350 pounds per square inch discharge. Consequently, for practical purposes I prefer to maintain a standard excess pressure in the sealing medium of 5 pounds, regardless of the

delivery pressure at which the compressor is operating.

If the fluid forcing device is operated as a vacuum pump I am able to produce a degree of vacuum equal to 99.997% of possible vacuum by maintaining a pressure in the lubricating and sealing medium of 5 pounds above atmosphere, that is to say, with the barometer standing at 29.0625 millimeters of mercury I am able to produce in a single stage device embodying my present invention a vacuum of 29.05 millimeters of mercury. By decreasing the pressure in the lubricating and sealing medium to 2 pounds, I am able to obtain only 95% possible vacuum, and by decreasing the pressure to 1 pound, 94% of possible vacuum is obtainable.

By supplying lubrication only in the fluid forcing device I am able to obtain a 93% vacuum which is approximately the vacuum which can be produced with the best reciprocating vacuum pumps operating under ideal conditions.

It is thought that the invention and numerous of its attendant advantages will be understood from the foregoing description and it is obvious that numerous changes may be made in the form, construction, and arrangement of the several parts without departing from the spirit or scope of my invention or sacrificing any of its attendant advantages, the forms herein described being preferred embodiments for the purpose of illustrating my invention.

Having thus described my invention, what I claim as new and desire to secure by Letters Patent is as follows:

1. A pump or compressor comprising a frame and co-operating relatively movable elements including a cylinder and a piston within the cylinder, said elements being mounted on the frame with the axis of the cylinder eccentric with respect to the axis of the piston whereby said elements define a work space therebetween, means on said cylinder for connecting the same drivingly with a source of power for rotating the cylinder about its axis, said cylinder having a wall opening in an end wall thereof and having a duct in the opposite end wall, said duct extending substantially radially in said end wall and opening axially on the inner surface of said wall, said duct having outer portions in communication with said work space, said piston being carried on a shaft secured to the frame against all movement, extending into the cylinder through said wall opening and having an end disposed opposite said axial duct opening, said shaft having a conduit in communication with said axial duct opening whereby a work medium delivered in said work space may pass through said shaft channel and said radial duct, and sealing means carried by the shaft and engaging the facing surface of the cylinder end wall around the axial opening of the duct.

2. A pump or compressor comprising a high pressure casing and co-operating relatively movable elements including a cylinder and a piston within the cylinder, said elements being mounted within said casing with the axis of the cylinder eccentric with respect to the axis of the piston whereby said elements define a work space therebetween, means on said cylinder for connecting the same drivingly with a source of power for rotating the cylinder about its axis, said cylinder having a wall opening in an end wall thereof and having a duct in the opposite end wall, said duct extending substantially radially in said end wall

and opening axially on the inner surface of said wall, said duct having outer portions in communication with said work space, said piston being carried on a shaft secured to the frame against all movement, extending into the cylinder through said wall opening and having an end disposed opposite said axial duct opening, said shaft having a conduit in communication with said axial duct opening whereby a low pressure work medium, delivered in said work space, may pass through said shaft channel and said radial duct, an annular seal carried by the shaft, yielding means urging said seal on the shaft to engage the facing surface of the cylinder end wall around the axial opening of the duct, said seal having a sealing flange externally exposed to the high pressure of the casing.

3. A pump or compressor comprising a frame, relatively movable elements on said frame including a rotary cylinder, rotatable on its axis and supported on said frame, and a piston within the cylinder and rotatable on an axis eccentric with respect to that of the cylinder whereby to define a work space between the cylinder and the piston, means to drivingly rotate said cylinder on its axis, means on said cylinder for connecting the same drivingly with a source of power for rotating the cylinder about its axis, said cylinder comprising spaced end plates and an annular ring clampingly secured between said end plates, a blade extending radially inwardly of said ring and engaging said end plates at its opposite edges and being clamped in place therebetween, said piston having a radial notch receiving said blade, the opposed sides of said notch forming seats, semi-cylindrical bearing blocks extending in the pockets of said notch between said end plates and engaging the opposed faces of said blade whereby to form a driving connection between said elements so that both may rotate together about their relatively eccentric axes, said piston having an internal chamber opening on an end surface of the piston, means to deliver a lubricating medium at a pressure above the maximum work-space pressure into said chamber, through a wall of said cylinder while the same is rotating, from whence it may penetrate between the engaging end surfaces of the piston and cylinder to lubricate the same, and duct means in said piston communicating said chamber with said notch to supply lubricant freely from the chamber into the notch to lubricate the engaging surfaces of said bearing blocks, block seats, and blade.

4. A pump or compressor as set forth in claim 3, wherein one of said cylinder end plates is formed with an opening concentric with the axis of the cylinder and the frame comprises a sleeve-like portion extending in said opening, bearing means in said opening for journaling said end plate on said sleeve, the other end plate of the cylinder having a projecting shaft journalled in the frame and forming means whereby the cylinder may be drivingly rotated, said shaft having an axially extending lubricant duct communicating, through said other end plate, with the interior of the cylinder and with the lubricant chamber in the piston, said frame being formed with a lubricant duct communicating with said chamber, means connecting said shaft duct, said piston chamber and said frame duct in a lubricant circulating system, and means to circulate a lubricant under pressure through said system whereby to lubricate the operating parts of said fluid pressure device.

5. Fluid forcing means comprising a rotary cylinder and a piston within the cylinder, said piston and cylinder having co-operating working surfaces and being relatively movable to accomplish the fluid forcing function and defining a work space therebetween, means to deliver a sealing medium, through a wall of the cylinder, while the same is rotating, in position to penetrate between the co-operating working surfaces of the cylinder and piston at a pressure of the order of five pounds per square inch in excess of the maximum pressure in said work space during the operation of the fluid forcing means whereby to prevent the escape of the work medium between said co-operating surfaces.

6. A vacuum pump comprising a rotary cylinder and a piston within the cylinder, said piston and cylinder having co-operating working surfaces and being relatively movable to accomplish 20 the fluid forcing function and defining a work space therebetween, means to deliver a sealing medium, through a wall of the cylinder, while the same is rotating, in position to penetrate between the co-operating working surfaces of the cylinder and piston at a pressure of the order of five pounds per square inch in excess of atmospheric pressure.

7. A compressor for the development of high pressures comprising a working stage embodying a rotary cylinder and a piston within the cylinder, said piston and cylinder having co-operating working surfaces and defining a working space and being relatively shiftable to accomplish compression of a work medium within said working space, means adjustable to deliver, through a wall of the cylinder, while the same is rotating, in position to penetrate between the working surfaces of said piston and cylinder, a lubricating and sealing medium under pressure of substantially five pounds per square inch in excess of the maximum pressure developed within said work space, in order to seal against the escape of the work medium between the co-operating surfaces of the piston and cylinder.

8. A pump or compressor comprising a frame forming a gas-tight dome, cooperating fluid forcing members on said frame within said dome and including a rotatable cylinder, a piston within the cylinder and disposed in eccentric tangential relation therewith, said cylinder including end plates secured at the opposite ends thereof and forming clearance spaces with the opposite ends of said piston, the circumferential surface of said piston defining a work space with said cylinder, partition means carried by and between said cylinder and piston in position dividing the work space into intake and discharge stages, means for relatively moving said fluid forcing members to produce a fluid forcing action, and a lubricating and sealing system operatively associated with said fluid forcing members and comprising means forming a reservoir for a sealing fluid at the discharge pressure prevailing in said dome, means to deliver a fluid sealing medium from said reservoir in said clearance spaces at a pressure in excess of that prevailing within the dome, means for returning excess sealing medium to said reservoir, and means operable outwardly of said dome to adjust the eccentric tangential relationship of said piston and cylinder.

9. A pump or compressor comprising a frame forming a gas-tight dome, cooperating fluid forcing members on said frame within said dome and including a rotatable cylinder, a piston within the cylinder and disposed in eccentric tangential

relation, said cylinder including end plates secured at the opposite ends thereof and forming clearance spaces with the opposite ends of said piston, the circumferential surface of said piston defining a work space with said cylinder, partition means carried by and between said cylinder and piston in position dividing the work space into intake and discharge stages, means for relatively moving said fluid forcing members to produce a fluid forcing action, and a lubricating and sealing system operatively associated with said fluid forcing members and comprising means forming a reservoir for a sealing fluid at the discharge pressure prevailing in said dome, means to deliver a fluid sealing medium from said reservoir in said clearance spaces at a pressure in excess of that prevailing within the dome, means for returning excess sealing medium to said reservoir, and means to cool the sealing medium as the same is delivered from the reservoir to said clearance spaces.

10 15 20 25

10. A pump or compressor comprising a frame and cooperating relatively movable elements including a cylinder and a piston within the cylinder, said elements being mounted on the frame

with the axis of the cylinder eccentric with respect to the piston whereby said elements define a work space therebetween, means for connecting one of the movable elements with a source of power for rotating the movable elements about their axes, said cylinder having a wall opening in an end wall thereof and having a duct in the opposite end wall, said duct extending substantially radially in said last-named end wall and opening axially on the inner surface of said last-named wall, said duct having outer portions in communication with said work space, an axially immovable shaft extending into the cylinder through said wall opening and having an end disposed opposite said axial duct opening, said piston being rotatably mounted on said shaft, and said shaft having a conduit in communication with said axial duct opening whereby a work medium delivered in said work space may pass through said shaft and said radial duct, and resilient sealing means carried by the shaft and having a resilient sliding engagement with the facing surface of the cylinder end wall around the axial duct opening.

WILLIAM W. WISHART.
